MECHANICAL TOY

Samuel I. Berger, Newark, N. J.

Application February 5, 1938, Serial No. 188,360
Renewed January 20, 1940

16 Claims. (Cl. 46—210)

The present invention relates to self-propelled toys of the type having a control member, which in successive operations alternately arrests and releases the motor of the toy.

5 An object of the invention is to provide a toy of the character described, which is simple, rugged and durable in construction and which is more positive and more dependable in its response to the operation of the control element 10 compared with heretofore conventional toys of this general type.

In the accompanying drawing in which is shown one of various possible embodiments of the several features of the invention:

15 Fig. 1 is a top plan view of my invention embodied in a vehicular toy.

Fig. 2 is a longitudinal section taken on line 2—2 of Fig. 1 but showing the toy in a stopped position.

20 Fig. 3 is a section taken on line 3—3 of Fig. 2.

Fig. 4 is a longitudinal section of a portion of the mechanism shown in Fig. 2 but showing said mechanism in arrested position, and

Fig. 5 is a detail section taken on line 5—5 of 25 Fig. 4.

Referring to the drawing, the toy is shown embodied in an automobile comprising a chassis 10 and a simple spring motor M mounted in the interior thereof, and desirably connected thereto by the usual tongue and slot connections well known in the toy art. This motor is set between a pair of spaced frame plates 11, which are joined together to provide a casing therefor, and which form journals for a winding shaft 13. 30 One end 14 of this shaft extends through an aperture (not shown) in the side of the chassis 10, and is polygonal in cross section to receive a winding key (not shown).

Mounted on the winding shaft 13 for rotation therewith is a ratchet plate 16, having prongs 17 cooperating with detent slots 18 in a spur main drive gear 20 loosely supported on said shaft. Affixed to this winding shaft 13 is one end of a powerful motor spring 22, the other end 23 being anchored to an end frame plate 24 forming part of the motor casing.

Also journaled in frame plates 11 is a wheel axle 26, driven from the main drive gear 20 by a gear transmission, which desirably includes a pinion 27 on said axle meshing with a spur gear 28 affixed to a countershaft 30, which carries a pinion 31 meshing with said main gear 20. The axle 26 carries the usual traction wheels 32.

In the operation of the spring motor, the rotation of winding shaft 13 in a clockwise direction

as viewed in Fig. 2 causes a winding of the motor spring 22 about said shaft, the prongs 17 of the ratchet plate 16 riding idly past the detent slots 18 of gear 20 during this operation. When the winding shaft 13 is released, the potential energy in the wound spring 22 rotates said shaft counterclockwise, and the resultant catching of the prongs 17 in the detent slots 18 effects the rotation of the wheels 32 in forward riding direction.

5 The means for controlling the stopping and going of the toy comprises a control member 40 in the form of a light vane, presenting a comparatively large area and desirably made of aluminum. This vane 40 is pivotally mounted 15 at 44 and is urged into a substantially horizontal position shown in Fig. 2 by a light leaf spring 45, one end of which is desirably soldered to an outward flange at 46 at the upper edge of one of the frame plates 11, the other end 48 curving downwardly and engaging the underside of said vane 40.

10 For pivotally mounting the control member 40, said member has at its forward end a downwardly inclined extension 41 of reduced width provided with a pair of spaced ears 42, which extend between a pair of upright brackets 43 connected to the frame plates 11, as for instance by soldering, and which are pivotally connected to said brackets by means of a pintle 44. The extension 20 25 41 has a tongue 50, the sides 51 of which are infolded to form a guide channel 52 for loosely receiving a slide piece 53 serving as a pawl. Cooperating with this pawl 53 is a ratchet wheel 30 35 54, fixed to a shaft 55 journaled in the frame plates 11 and extending parallel to the hinge support 44 of vane 40. This ratchet wheel 54 is in the form of a spur gear having teeth 56 cut with a rake, so that one side 57 of each tooth is nearly straight and extends substantially radially of the wheel, the other side 58 being inclined with respect thereto, and desirably convexly curved.

Also fixed to the shaft 55 is a cam 60 desirably in the form of a spur wheel, spaced from the ratchet wheel 54 by a collar 61, which is desirably formed integral with one of said wheels. The number of teeth on this cam wheel 60 is one-half that on the ratchet wheel 54, so that as said ratchet wheel is rotated one tooth, the cam wheel 60 is rotated one-half a tooth.

40 45 50 55 Cooperating with the ratchet wheel 54 to prevent its retractive rotation is a detent 65, having a pair of spaced depending ears 65a mounted on a hinge pin 66 supported in the frame plates 11. This detent 65 also has a pair of spaced depend-

ing lugs 68 overlying opposite sides of the ratchet wheel 54 to center said detent with respect to said wheel. The outer end 70 of the detent 65 is bent downwardly to form a hook, adapted to engage 5 and catch the straight sides 57 of the ratchet teeth respectively as said teeth are moved step by step in a counterclockwise direction successively past said hook.

Cooperating with the cam wheel 60 is a brake 10 71 desirably in the form of a lever, pivotally mounted on a shaft 72 supported in the frame plates 11. This lever 71 has an upright arm 73 and a substantially horizontal arm 74 serving as a weighted member for urging the lever counterclockwise as viewed in Figs. 2 and 4. The upper end of the arm 73 has a substantially V-shaped cam follower section 75 on one side in engagement with the teeth of the cam wheel 60, and a stop section 76 on the other side, cooperating 15 with a dog 80 affixed to a shaft 81 supported on the frame plates 11. This shaft 81 is desirably in the form of an elongated pinion driven counterclockwise from the spring motor M by a drive mechanism, which desirably comprises spur 20 gear 82 meshing with said gear shaft 81 and secured to a shaft 83. Also mounted on said shaft 83 is a pinion 84, which meshes with a spur gear 85 mounted on a shaft 86 supported on frame plates 11. This shaft 86 carries a pinion 25 87 meshing with a spur gear 88 secured to a shaft 89 journaled in frame plates 11. Also mounted on this shaft 89 is a pinion 90 meshing with the main drive gear 20.

In the operation of the device, when the toy 30 35 is immobilized, the cam follower 75 will rest on the outer end of one of the teeth of the cam wheel 60 as shown in Fig. 2. In this position, the stop section 76 of the cam follower will be in the path of counterclockwise rotation of the dog 80, so that said dog will engage the upper edge of said stop section 76 and the operation of the spring motor M is blocked.

Upon the application of pressure to the top of the vane 40, as for instance by the player blowing air from his mouth through slots 39 in the top 40 45 of the chassis 10, the vane 40 will be swung clockwise about its pivotal support 44 against the action of the spring 45, so that the pawl 53 engaging the straight side 57 of the tooth 56 directly above it will move the ratchet wheel 54 counterclockwise. Lugs 79 extending upwardly from the frame plates 11 will act as stops to limit the clockwise angular movement of the vane 40 to correspond to advance of the ratchet wheel 54 to an 50 55 angular amount equal to one tooth.

The catch 70 engaging the straight side 57 of the adjacent ratchet tooth 56 directly below acts as a detent to prevent return movement of wheel 54.

When the pressure on the vane 40 is released, it 60 will swing back into horizontal position under the action of spring 45 into engagement with the bottom side of the top of the chassis 10. This return movement of the vane 40 causes the slide 65 70 pawl 53 to ride idly over the inclined side 58 of the tooth 56 directly below it until it drops into the next succeeding interdental space. Although the top of the chassis is shown as a stop for the return movement of the vane 40, as far as certain aspects of the invention are concerned, the stop may be in the form of an upright bracket connected to the motor casing and having an offset at its upper end adapted to engage the rear or side of said vane.

75 The counterclockwise rotation of the ratchet

wheel 54 in the last movement described, will cause a corresponding rotation of the cam wheel 60 a distance equal to one-half a tooth so that the cam follower 75 under the weighted action of the arm 74 will drop into the interdental space 5 of said wheel 60 directly below it from the position shown in Fig. 2 to the position shown in Fig. 4. In this position of the cam follower 75, the stop 76 thereof will be out of the path of rotation of the dog 80, so that said dog will be 10 free to rotate, and the device will be able to continue its locomotion. The next succeeding impulse imparted to the vane 40 will cause the rotation of the ratchet wheel 54 and the cam wheel 60 one step into the phase shown in Fig. 2 in 15 which the spring motor is again locked or braked. Although the control member 40 is shown in such form as to be responsive to a blast of breath air blown thereagainst, it may be in the form of an ordinary finger piece accessible from the outside of the chassis and operated by application of finger pressure thereon.

Also as far as certain aspects of the invention are concerned, it is not limited to the control of the locomotion of a toy of the vehicular type, but may be embodied in a form to effect the control of certain amusing operations of a toy of the non-vehicular type.

As many changes could be made in the above construction, and many apparently widely different embodiments of this invention could be made without departing from the scope of the claims, it is intended that all matter contained in the above description or shown in the accompanying drawing shall be interpreted as illustrative and not in a limiting sense.

Having thus described my invention, what I claim as new and desire to secure by Letters Patent is:

1. A toy of the self-propelled type including a 40 spring motor therefor, a control member, a member rotatable by said spring motor, a cam, a ratchet mechanism between said control member and said cam for rotating said cam step by step by successive impulses imparted to said control 45 member, and a brake member in cam follower engagement with said cam, and oscillated by said cam alternately into and out of the path of rotation of said rotatable member, whereby successive impulses imparted to said control member will cause alternate arrest and release of said spring motor.

2. A toy of the self-propelled type including a 50 spring motor therefor, a control member, a member rotatable by said spring motor, a cam spur gear, a ratchet mechanism between said control member and said cam for rotating said cam step by step by successive impulses imparted to said control member, and a brake member in cam follower engagement with the teeth of said cam wheel, and oscillated by said cam wheel so that said brake will be alternately in engagement with the outer end of the cam teeth and in an interdental space of said wheel, said brake in said alternate phases being in and out of the path of rotation respectively of said rotatable member, whereby successive impulses imparted to said control member will cause alternate arrest and release of said spring motor.

3. A toy of the self-propelled type including a 55 spring motor therefor, a control member, a rotatable member having a drive connection with said spring motor, a brake member, and means responsive to successive impulses imparted to said control member for oscillating said brake mem- 60 ber.

ber alternately into and out of blocking engagement with said rotatable member respectively, whereby successive impulses imparted to said control member will cause alternate arrest and release of said spring motor.

5. A toy of the self-propelled type including a spring motor therefor, a control member, a ratchet mechanism including a ratchet wheel rotated step by step by successive impulses imparted to said control member, a member rotatable by said spring motor, and a stop member oscillated in conformity with the step by step rotation of said ratchet wheel, and alternately into and out of the path of rotation of said rotatable member, whereby successive impulses imparted to said control member will cause alternate arrest and release of said spring motor.

10. A toy of the self-propelled type including a spring motor therefor, a sensitive control member, a ratchet mechanism including a ratchet wheel rotated step by step by successive impulses imparted to said control member, a member rotatable by said spring motor, and a pivoted stop member angularly oscillated in conformity with the step by step rotation of said ratchet wheel, and alternately into and out of the path of rotation of said rotatable member, whereby successive impulses imparted to said control member will cause alternate arrest and release of said spring motor.

15. A toy of the self-propelled type including a spring motor therefor, a sensitive control member, a ratchet mechanism including a ratchet wheel rotated step by step by successive impulses imparted to said control member, a cam member rotated step by step in conformity with the step by step rotation of said ratchet wheel, a dog rotated from said spring motor, and a stop member cooperating with said cam and movable thereby alternately into and out of the path of rotation of said dog by the successive step by step movements of said cam, whereby successive impulses on said control member will cause alternate arrest and release of said spring motor.

20. A toy of the self-propelled type including a spring motor therefor, a control member, a ratchet mechanism including a shaft and a ratchet wheel affixed to said shaft and rotated step by step by successive impulses imparted to said control member, a cam member affixed to said shaft for rotation with said ratchet wheel, a dog rotated from said spring motor, and a stop member cooperating with said cam and movable thereby alternately into and out of the path of rotation of said dog by the successive step by step movements of said cam, whereby successive impulses on said control member will cause alternate arrest and release of said spring motor.

25. A toy of the self-propelled type including a spring motor therefor, a control member, a ratchet mechanism including a ratchet wheel rotated step by step by successive impulses imparted to said control member, a cam spur wheel rotated step by step in conformity with the step by step rotation of said ratchet wheel, a dog rotated from said spring motor, and a stop member cooperating with said cam and movable thereby alternately into and out of the path of rotation of said dog by the successive step by step movements of said cam, whereby successive impulses on said control member will cause alternate arrest and release of said spring motor.

30. A toy of the self-propelled type comprising a spring motor therefor, a control member, a ratchet mechanism including a shaft, a ratchet

35. spur wheel affixed to said shaft, and a pawl connected to said control member and adapted to rotate said ratchet wheel step by step by successive impulses imparted to said control member, a cam spur wheel having one-half the number of teeth of said ratchet wheel and affixed to said shaft for rotation step by step in unison with the step by step rotation of said ratchet wheel, a dog rotated from said spring motor, and a stop member cooperating with said cam wheel and movable thereby so as to engage the outer end of a tooth of said cam wheel during alternate step by step phases of said cam wheel, said stop member in the latter phases being in the path of rotation of said dog, said stop during the other step by step phases of said cam wheel extending in the interdental spaces of said cam wheel and out of the path of rotation of said dog, whereby successive impulses on said control member will cause alternate arrest and release of said spring motor.

40. A toy of the self-propelled type including a spring motor therefor, a pivotally mounted control member, a pawl connected to said control member and angularly movable therewith about the pivotal support of said member, a ratchet wheel cooperating with said pawl and having an axis extending substantially parallel to the axis of the pivotal connection of said control member, a member rotatable from said spring motor, a stop member, and means responsive to the step by step movement of said ratchet wheel for oscillating said stop member alternately into and out of the path of rotation of said rotatable member, whereby successive impulses on said control member will cause alternate arrest and release of said spring motor.

45. 11. A toy of the self-propelled type including a spring motor therefor, a pivotally mounted control member having a guide channel formation secured thereon, a pawl slidably mounted in said channel formation, a ratchet wheel cooperating with said pawl and rotated thereby step by step by successive impulses imparted to said control member, a member rotatable from said spring motor, a brake member and means responsive to the step by step movement of said ratchet wheel for oscillating said brake member alternately into and out of the path of rotation of said rotatable member, whereby successive impulses on said control member will cause alternate arrest and release of said spring motor.

50. 12. A toy of the self-propelled type including a spring motor therefor, a pivotally mounted control member having a downwardly inclined guide channel formation at one end thereof, a pawl slidably mounted in said channel formation, a ratchet wheel cooperating with said pawl and rotated thereby step by step by successive impulses imparted to said control member, a member rotatable by said spring motor, and means responsive to the step by step movement of said ratchet wheel for alternately blocking and unblocking the rotation of said rotatable member, whereby successive impulses on said control member will cause alternate arrest and release of said spring motor.

55. 13. A toy of the self-propelled type including a spring motor therefor, a pivotally mounted sensitive control member adapted to be moved about its pivotal support by successive impulses created by blowing breath air thereagainst, and having a downwardly inclined guide channel formation at one end thereof, a pawl slidably mounted in said channel formation, a shaft, a ratchet wheel

on said shaft cooperating with said pawl and rotated step by step by successive impulses imparted to said control member, a rotatable dog having a drive connection with said spring motor, a cam spur wheel also on said shaft and rotated in step by step unison with said ratchet wheel, said cam spur wheel having one-half the number of teeth of said ratchet wheel, and a pivotally mounted brake member in cam follower engagement with the teeth of said cam wheel and oscillated thereby alternately into and out of blocking engagement with said rotatable dog by the successive step by step movements of said cam wheel, whereby successive impulses on said control member will cause alternate arrest and release of said spring motor.

14. A toy of the self-propelled type including a spring motor therefor, a sensitive control member, a rotatable member having a drive connection with said spring motor, a cam, means between said control member and said cam for rotating said cam step by step by successive impulses imparted to said control member, and a pivoted brake member having a pair of arms in angular relationship, one of said arms being in cam follower engagement with said cam, and the other arm serving as a weight for urging said cam follower arm into engagement with said cam, said brake being oscillated by the step by step movement of said cam to move said cam follower arm alternately into and out of blocking engagement with said rotatable member, whereby successive impulses on said control member will cause alternate arrest and release of said spring motor.

15. A vehicular toy of the self-propelled type including a pair of traction wheels, a spring motor for driving said wheels, a control member, a member rotatable by said spring motor, a cam, a ratchet mechanism between said control member and said cam for rotating said cam step by step by successive impulses imparted to said control member, and a brake member in cam follower engagement with said cam and oscillated by said cam alternately into and out of the path of rotation of said rotatable member, whereby successive impulses imparted to said control member will cause alternate arrest and release of said spring motor and will cause corresponding alternate arrest and locomotive movement of said toy.

16. A vehicular toy of the self-propelled type including a chassis, a spring motor in said chassis, a pair of traction wheels driven from said motor, a light pivotally mounted vane in said chassis closely adjacent to the top thereof, said chassis top having a series of slots through which air may be blown from the operator's mouth to move said vane about its pivotal connection, a member rotatable by said spring motor, a cam, a ratchet mechanism between said vane and said cam for rotating said cam step by step by successive impulses imparted to said vane, and a brake member in cam follower engagement with said cam and oscillated by said cam alternately into and out of the path of rotation of said rotatable member, whereby successive impulses imparted to said vane by blowing successive blasts of air thereagainst through said chassis slots will cause alternate arrest and release of said spring motor.

SAMUEL I. BERGER. 35
